UNITED STATES PATENT OFFICE

114,851

DESIGN FOR A SYMMETRICALLY SECTIONED, ALL WING CANTILEVER MONOPLANE

James G. Taylor, Fairfield, and Oscar A. Swanson, Dayton, Ohio, assignors to the Government of the United States of America, as represented by the Secretary of War, and his successors in office

Application July 31, 1935, Serial No. 57,884

Term of patent 7 years

To all whom it may concern:

Be it known that we, James G. Taylor and Oscar A. Swanson, citizens of the United States, residing at Fairfield and Dayton, respectively, in the counties of Greene and Montgomery, respectively, and State of Ohio, have invented a new, original, and ornamental Design for a Symmetrically Sectioned, All Wing Cantilever Monoplane, of which the following is a specification, reference being had to the accompanying drawing, forming part thereof, wherein:

Fig. 1 is a top plan view of an airplane showing our new design;

Fig. 2 is a front elevational view of the said

airplane design with the landing gear fully retracted as in flight; and

Fig. 3 is a side elevational view of said airplane design with the landing gear shown in dotted lines.

The dominant feature of our design resides in the fuselage and its arrangement with the wings and empennage.

We claim:

The ornamental design for a symmetrically sectioned, all wing cantilever monoplane, as shown and described.

JAMES G. TAYLOR.
OSCAR A. SWANSON.
